UNITED STATES PATENT OFFICE.

THOMAS J. BROWN, OF CRESTWOOD, KENTUCKY.

ENVELOP.

1,141,312.

Specification of Letters Patent.

Patented June 1, 1915.

Application filed June 30, 1914. Serial No. 848,233.

To all whom it may concern:

Be it known that I, THOMAS J. BROWN, a citizen of the United States, residing at Crestwood, in the county of Oldham and 5 State of Kentucky, have invented certain new and useful Improvements in Envelops; and I do hereby declare the following to be a full, clear, and exact description of the invention, such as will enable others skilled 10 in the art to which it appertains to make and use the same. .

This invention relates to envelops, and more particularly to that type generally known as the "outlook" in which is provided a section of transparent paper or other material covering an opening in the front of the envelop whereby the heading of the letter, bill or other inclosure is visible. The objection to the ordinary type of envelop of 20 this character is that except by very accurately folding and fitting the letter or other inclosure within the envelop and placing the heading on the inclosure at a certain point, the inclosure is liable to move to a position 25 where the heading thereof is not visible through the transparent section, and thus considerable time of the postal clerks is lost in adjusting the inclosures of the envelops to make the address visible.

30 It is the object of this invention to provide reliable and efficient means for simultaneously securing the flap of the envelop and its inclosure in accurate position behind the section of transparent material.

35 With this and other objects in view, the invention consists in the novel construction, combination and formation of parts as will be hereinafter specifically described, claimed and illustrated in the accompanying drawings, in which:

Figure 1 represents a plan view of the envelop, showing the flap in extended position. Fig. 2 represents a plan view of the envelop, showing the flap closed and sealed. 45 Fig. 3 represents an enlarged detail sectional view on the line 3—3 of Fig. 2.

Referring to the drawing in detail, wherein similar reference numerals designate corresponding parts throughout the several 50 views, the numeral 5 indicates the front of the envelop having one of its ends suitably shaped to provide a flap 6 and having the

opposite end portion doubled upon itself to provide the back or rear wall 7. In the ordinary envelop of this character provided with 55 the transparent section of material, the opening in the body of the envelop is formed in the front thereof, whereas I provide the opening, designated by the numeral 8, in the back 7 of the envelop, whereby the position of the contents of the envelop are visible while the flap 6 is being sealed. The usual transparent material 9 is secured over the opening 8 and against the inner face of 60 the back 7.

The back 7 is secured at its ends to the body or front 5, and the flap 6 is adapted to be folded on the dotted line 10. An opening 11 is formed in the back 7 of the envelop and is adapted to receive the tongue 12 70 formed in the gummed end portion 13 of the flap 6. While I have here shown the tongue 12 of tapered formation, it will be understood that the size and shape thereof may be varied as desired, or to meet various 75 requirements.

In use, the inclosure 14 bearing the address of the addressee is positioned within the envelop in proper position behind the section of transparent material 9. The flap 80 6 of the envelop is subsequently folded and sealed in the usual manner, thus simultaneously securing the flap 6 to the back 7 and securing the inclosure in proper position behind the material 9. 85

What I claim is:

An envelop including a back having large and small openings therein, a transparent covering for said large opening, a flap having the marginal portion gummed, and a 90 tongue struck out from the gummed portion of said flap lying entirely within the edge of the latter and adapted to overlie and extend through said small opening when said flap is closed and secure the contents of the 95 envelop in adjusted position behind said transparent covering.

In testimony whereof I affix my signature in presence of two witnesses.

THOMAS J. BROWN.
